CERTIFICATE HOLDER AND MEANS FOR SECURING THE SAME TO A SUPPORT

George A. Stanzel, Des Moines, Iowa

Application October 24, 1938, Serial No. 236,625

7 Claims. (Cl. 40—10)

The object of my invention is to provide an improved certificate holder of that type adapted to be secured preferably to the steering post of an automobile in such a manner that the information contained on the certificate may be easily read by persons standing outside of the car and looking through the front window.

More specifically, it is the object of my invention to provide a certificate holder of simple, durable and inexpensive construction which may be easily and quickly applied to the steering post of an automobile or other similar support, and when so applied the certificate holder enclosed or fastened in such a manner that the certificate cannot be removed from the holder or the holder removed from the support without damaging the certificate holder or its fastening means or a suitable seal used in connection therewith.

A further object of my invention is to provide in a certificate holder formed of two flexible members one superimposed on the other, and one of which is transparent, having their edges bound to form a container and adapted to be curved around a support, an improved means whereby the transparent member may be stretched relative to the other member to accommodate the differences in the length of their circumferential surfaces as the certificate holder is wrapped around a support.

A further object of my invention is to provide in a certificate holder of the type above described, improved means for sealing the holder against being opened and against being removed from the support after being placed thereon.

My invention consists in the construction, arrangement and combination of the various parts of the device, whereby the objects contemplated are attained, as hereinafter more fully set forth, pointed out in my claims, and illustrated in the accompanying drawing, in which:

Figure 1 is a plan view of my improved certificate holder showing the certificate placed therein in dotted lines.

Figure 2 is a perspective view of the back side of the same.

Figure 3 is a perspective view of the transparent and flexible sheet which forms the body portion of my improved holder, the same being partially folded before receiving the clips for binding the edges of the same.

Figure 4 is a perspective view of the same showing the binding clips applied and a certificate partially placed in the envelope formed by said binders.

Figure 5 is an enlarged detail sectional view taken on the line 5—5 of Figure 1.

Figure 6 is an enlarged detail sectional view taken on the line 6—6 of Figure 4.

Figure 7 is an enlarged detail sectional view taken on the line 7—7 of Figure 4.

Figure 8 is a transverse sectional view of a steering post showing the manner in which the certificate holder is secured thereto, the certificate holder being illustrated in end elevation.

Figure 9 is a perspective view of the form of seal which is preferably used in connection with my improved holder.

Figure 10 is a perspective view of the back side of a modified form of my improved holder.

Figure 11 is a detail sectional view taken on the line 11—11 of Figure 10.

My improved certificate holder is formed preferably of a longitudinal sheet of flexible and transparent material such as Celluloid, and is designated by the numeral 10, said sheet being folded to form a central body portion 11, an end portion 12 and a second end portion 13, the free end of the member 13 being cut on inwardly extending lines 14 terminating in laterally extending lines 15 to form wing sections 16, said wing sections being doubled outwardly overlapping the portion 17, the said portions then being perforated and provided with eyelets 18. The end member 12 is folded over and adjacent to the body portion 11, said portions having their side edges 19 bound together by metallic binding strips 20, said members 20 being formed of strips of metal bent centrally and longitudinally and having one side portion overlapping the other to form grooves 21 for receiving the edges 19 in the manner clearly illustrated in Figure 4, the binders being placed under a suitable press and squeezed together.

At the same time suitable dies are included in the press for forcing the metallic tongues 22 of the lower portions of the binder upwardly through the members 11 and 12 and into corresponding slots formed in the upper portions of the binders, in the manner as illustrated in Figures 4, 6 and 7, thus providing means for anchoring the binders to the members 11 and 12 so that the edges 19 will be firmly held together. By this construction an envelope is formed with space between the members 11 and 12 for receiving a certificate 23.

The central portion of the binding strips 20 are provided with perforations 24 in which suitable eyelets may also be placed, if so desired, said eyelets passing through both both sides of the strip 20 and the edges of the members 19, thus providing further means for anchoring the binding strips against sliding off of the edges of the 55

comparatively smooth hard-surfaced material such as Celluloid. The member 13 is then folded downwardly overlapping the corresponding end of the member 12 with the openings 18 over and in alinement with the perforations 24, in the manner illustrated in Figure 2. A flexible tie is then provided which is preferably formed of twisted fibrous wire 25 having a block 26 fixed to one end, said block being formed of comparatively soft material, such as lead, to form a seal, and provided with openings 27 and 28. One end of the tie wire 25 is then placed through one set of openings 18 and 24, after which the free end of the tie is placed through the opening 27 to form a loop 29 for securing the free end of the member 13 to the back side of the member 12. The holder is then placed adjacent to a suitable support 30, such as the steering post of an automobile, with the binders extending longitudinally of the post, the holder is then curved around the post in the manner illustrated in Figure 3, after which the free end of the tie 25 is placed through the other openings 18 and 24 and then again returned to the member 26 and passed through the opening 28 of the member 26, thus providing means for tying or fastening the certificate holder to the support, at the same time fastening the envelope closed with the member 13 between the body portion of the certificate holder and the steering post. The outer edge of the member 26 is then placed in a suitable tool for crushing a portion or body of the member 26 to cause it to firmly grip the free end of the member 25 and thus provide means for sealing the certificate holder closed and to its support, whereby the certificate cannot be removed without destroying or defacing the certificate holder or breaking the tie or destroying the seal, thus preventing the stealing of the certificate holder and transferring the same from one car to another.

It will readily be seen that since the members 11 and 12 are of the same width and have their overlapping edges bound firmly together, that if the certificate holder thus formed is wrapped around the steering post, then the outer ones of said members will be bent in a circumferential surface of a greater diameter than the inner one, which would tend to separate the bound edges. To overcome this difficulty I have provided the member 11 with longitudinally extending corrugations 31 wherein the material is stretched as the said corrugations are formed, so that when the certificate holder is wrapped around the steering post said corrugations will flatten out and permit the member 11 to stretch relative to the member 12.

In Figures 10 and 11 I have illustrated a modified form in which the member 13a is cut diagonally across its end so that the said overlapping portion is secured to the body portion at one corner instead of two corners, as is illustrated in Figure 2. The other overlapping portion 12a is made shorter and is bound under the members 12 similar to my preferred form. In this form a sheet of stiff non-transparent or opaque material 32 may be inserted between the members 12a and 13a to form a backing for the certificate. The certificate is then placed between the member 32 and the member 11a.

Thus it will be seen I have provided a certificate holder of simple construction in which all sewing is eliminated and in which the envelope or body portion may be formed of transparent and comparatively brittle material, such as Cel-

luloid, and when so formed the adjacent overlapping edges will be firmly bound with a metallic binder to prevent tearing and provided with means whereby after a certificate has been placed in position the envelope may be closed and sealed and fixed to its support in such a manner that the certificate cannot be removed without defacing or tearing the holder or destroying the fastening means or the seal, thereby enabling traffic officers to ascertain at a glance whether or not the certificate is one that has been assigned to the particular car being investigated.

I claim as my invention:

1. A certificate holder formed of thin flexible and transparent material folded to form a body and end portions, one of the end portions being folded over the body portion, a binder formed of rigid material securing the adjoining side edges of said body and overlapping end portion together to form an envelope with the other end portion adapted to overlap the first end portion to close said envelope after a certificate has been placed in the envelope, and means for fastening and sealing the last overlapping end portion to said body and for mounting and sealing the certificate holder to a suitable support.

2. A certificate holder formed of thin flexible and transparent material folded to form a body and end portions, one of the end portions being folded over the body portion, a binder formed of rigid material securing the adjoining side edges of said body and overlapping end portion together to form an envelope with the other end portion adapted to overlap the first end portion to close said envelope after a certificate has been placed in the envelope, flexible means for fastening the last overlapping end to said body and for mounting the certificate holder to a suitable support, and means for sealing the flexible means whereby the envelope cannot be opened or the certificate holder removed without breaking said seal.

3. A certificate holder adapted to be placed around a support, comprising a transparent flexible front portion and a super-imposed flexible back portion, means binding two opposite and adjoining side edges of said portions together to receive a certificate between them, the front portion being corrugated longitudinally to permit the front portion to be stretched relative to the back portion as the holder is bent around a support, and means for fastening the holder to a support.

4. A certificate holder, comprising a strip of flexible and transparent material folded to form a body and end portions, one end portion overlapping the body portion, a strip of non-transparent material between said body portion and said overlapping end portion, means binding together the side edges of said body portion and the corresponding edges of said non-transparent material and the side edges of said overlapping end portion, and means secured to said binding means for fastening said holder to a support.

5. A certificate holder adapted to be placed around a support, comprising a front portion and a back portion to receive a certificate between them, one portion being corrugated longitudinally to permit its area to change to compensate for the differences in areas between the inner and outer surfaces due to their differences in diameter as they are wound around a support.

6. The combination of a support, a closed certificate holder having a passage for the insertion of a certificate, means for closing said passage having its free edge provided with a perforation,

5 said certificate holder being supported adjacent to said support and having two of its opposite edges perforated, a seal having a plurality of openings, a flexible tie passed through one of the openings of said seal, thence through the perforation of said closing means and one of the perforations of said holder and thence through another one of the openings of said seal, thence around said support, thence through the other perforation of said holder, thence back to and through another one of the openings of said seal, to be clamped therein by a suitable seal-applying tool whereby the certificate with said holder cannot be removed without destroying the holder or its fastening means.

10

15 7. The combination of a support, a closed cer-

5 tificate holder having a passage for the insertion of a certificate, said certificate holder being supported adjacent to said support and having two of its opposite edges perforated, a seal having a plurality of openings, a flexible tie having one end fixed in one of said openings of said seal, the other end of said tie being passed through one of said perforations of the holder, thence around said support and through the other perforation of said holder, thence returned again 10 around said support through another one of the openings of said seal, to be clamped therein by a suitable seal-applying tool whereby the certificate with said holder cannot be removed without destroying the holder or its fastening means. 15

GEORGE A. STANZEL.
